UNITED STATES PATENT OFFICE.

PATRICK O'CONNELL, OF JOHNSTOWN, PENNSYLVANIA, ASSIGNOR TO THE JOHNSON COMPANY, OF SAME PLACE.

INTERLOCKING BRACE-CHAIR FOR RAILROAD-RAILS.

SPECIFICATION forming part of Letters Patent No. 409,114, dated August 13, 1889.

Application filed April 22, 1889, Serial No. 308,186. (No model.)

To all whom it may concern:

Be it known that I, PATRICK O'CONNELL, of Johnstown, in the county of Cambria and State of Pennsylvania, have invented a new and useful Interlocking Brace-Chair for Railroad-Rails, which invention is fully set forth and illustrated in the following specification and accompanying drawings.

The object of this invention is to make a strong and durable interlocking brace-chair of the form commonly known as a "box-chair."

The invention will first be described in detail, and then particularly set forth in the claims.

15 In the accompanying drawings, Figure 1 shows the chair in end elevation mounted on a cross-tie and supporting a girder-rail, shown in cross-section. Fig. 2 shows one side or brace portion of the chair detached in perspective. Fig. 3 shows the other side or seat portion of the chair detached in perspective. Fig. 4 shows in end elevation, having a rail mounted thereon, a modification of the chair shown in Fig. 1. Fig. 5 shows detached in perspective the seat portion of the chair shown in Fig. 4. Fig. 6 shows in end elevation, with a rail mounted thereon, another modification of the chair shown in Fig. 1, the whole secured to the cross-tie. Fig. 7 shows in perspective, 30 detached, one side or the seat portion of the chair shown in Fig. 6. Fig. 8 shows in perspective the other side or brace portion of the chair shown in Fig. 6, detached.

In said figures the several parts are indicated by reference-letters as follows:

The letter A indicates the brace portion of the chair, having the brace proper C at its upper portion for bracing the rail H.

40 The letter B indicates the seat portion of the chair for the base of the rail, provided with the lug D for clamping the flange of the rail.

The letters d d are the flanges or feet of the chair, through which the chair is secured to the cross-tie of the track by spikes or in any other well-known manner.

The letter a indicates locking-lugs stamped out of or otherwise formed on the side A.

50 The letter b indicates locking-lugs stamped out of or formed on the side B. When these two sides of the chair are put together, the

lugs a and b interlock and render said two sides A and B of mutual support to each other and the rail.

The form of rail employed may be that of any well-known cross-section, two well-known forms of girder-rail being illustrated in the drawings.

In Fig. 4 the chair is shown with double brace portions E and F and a supporting rail-seat G, secured to the two sides E and F.

The letters C C indicate, respectively, the brace portions proper of the two sides E and F, and the letters e and f indicate, respectively, interlocking lugs stamped out of the sides E and F.

The letters g g indicate the lugs stamped out of the rail-seat G.

This double brace shown in Fig. 4 is preferable to be used at the joints where two rails meet, as at such points the splice-bar fit of the double brace is preferable, acting on both sides of the rail instead of on but one side, as shown in Figs. 1 and 6. The bolt J (shown in Fig. 4) locks the two portions of the chair together through the web of the rail H, and said bolt is of advantage in drawing the brace portions proper well into the rail. Four of these bolts may be used in the whole length of the chair, two bolts passing through each end of each rail. These chairs, being used at the joints, are of extra length, as is indicated by the length of the rail-seat G. (Shown in Fig. 5.)

It will be understood, of course, that the brace or braces proper C could be replaced by lugs or keepers—such as D—on either side of the rail, if desired, the upper portion of the braces C being omitted.

The parts of this form of box-chair, as indicated in the several figures, are constructed so as to interlock, forming a firm track-chair when put together with the rail mounted thereon in place.

In Fig. 6 the lug b fits through the slots b', 95 as separately shown in Figs. 7 and 8.

This chair can be made of either wrought or cast metal, as may be preferred.

Having thus fully described my said rail-chair, as of my invention I claim—

1. An interlocking brace-chair of box form for railroad-rails, having a rail-seat provided

with lugs to interlock the parts of the chair and clamp the rail to the chair, substantially as set forth.

2. A two-part chair of box form for railroad-rails, provided with a rail-seat secured to the two parts or sides of the chair by interlocking lugs, substantially as set forth.

3. A two-part brace-chair of box form for

railroad-rails, provided with a rail-seat secured to the two parts or sides of the chair by interlocking lugs and by bolts to the rails of the track, substantially as set forth.

PATRICK O'CONNELL.
